**VERTICALLY AND LATERALLY EXPANSIBLE
CONTINUOUS MINING MACHINE**

Clifford H. Snyder, Dormont, Pa., and Harry Calvin Funk, Salem, Ohio, assignors, by mesne assignments, to The Colmcil Company, New Lexington, Ohio, a corporation of Ohio

Application September 8, 1949, Serial No. 114,556

17 Claims. (Cl. 262—9)

This invention relates generally to mining, mining methods and practices and more particularly to method and apparatus for chipping coal by overlapping rotary chipping heads that are expansible horizontally and vertically to accommodate different widths of mining cuts and different heights of coal seams.

In some coal mining fields the coal seam is substantially uniform in dimension and lies substantially horizontal whereas other coal fields contain seams of coal that vary in height and also slope in one or several directions. Upon exploration by surface boring in a coal field that is to be developed for mining, detailed data may be accumulated to complete maps showing the variations of the coal seam throughout the field, together with the character of the coal. This information permits the mining engineer to properly and expeditiously lay out the main haul entries and ventilating entries together with the complete layout and progressive work to be carried on for opening and removing the coal from the entire field. The more detailed the exploration is carried out the more accurately the planning and execution of the mining as to the location and size of the entries and rooms required to remove the coal under a specific mining practice.

The purpose of this invention is the provision of method and apparatus that enables the development of a mine by progressive continuous mining. To accomplish this purpose it is advantageous to employ a continuous machine that is capable of continuously digging the coal along a prescribed path and which can vary the width as well as the height of the tunnel being cut and also follow the slope or drift of the coal seam as it changes.

Another and very important object and advantage of the continuous mining machine comprising this invention resides in the fact that the expansion of the cutting mechanism horizontally as well as vertically permits greater maneuverability of the machine in the mine as the tunnel cut is larger than the machine, permitting it to cut rooms at right angles to the entries which provides stronger and safer ribs without varying the sizes of the entries or rooms.

Another object is the provision of a mining machine having horizontally and vertically retractible rotary cutting members or cutting heads permitting the machine to maneuver between timbering posts and under cross timbers.

Other objects and advantages appear hereinafter in the following description and claims.

The accompanying drawings show, for the purpose of exemplification without limiting the invention or claims thereto, certain practical embodiments of the invention wherein:

Fig. 1 is a view in side elevation of the forepart of the machine comprising this invention;

Fig. 2 is a view in vertical section of the structure shown in Fig. 1;

Fig. 3 is a front elevation of the machine shown in Figs. 1 and 2;

2

Fig. 4 is a vertical section taken on the lines 4—4 of Fig. 1;

Fig. 5 is a top plan view of the machine as shown in the previous figures.

Fig. 6 is a front elevation of the machine illustrating a rotary type of cusp cutter; and

Fig. 7 is a side elevation of Fig. 6 with parts being broken away.

Referring first to Figs. 1 and 5, the continuous mining machine comprising a frame 1 consists of the side members 2 and 3 which are connected together by lateral members to form a rigid body member. This body member carries the top idler rollers 4 and the bottom track rollers 5 together with suitable end sprocket wheels such as shown at 6 for the support and drive of the endless tracks 7 and 8. The endless tracks 7 and 8 are independently propelled by hydraulic motors, not shown, which obtain their power from the pump 9, as shown in Fig. 2, that is driven by the electric motor 10, which is preferably a variable speed motor. The motors driving the endless tracks 7 and 8 are also independently controlled for providing complete maneuverability of the body 1.

The forward ends of the frames 2 and 3 of the body 1 are provided with vertically extending T-shaped ways 11 and 11a which project beyond the ends of the tracks 7 and 8 as shown in Fig. 5 and are arranged to receive complementary channels in the upper and lower center castings 12 and 13 as shown in Figs. 2 to 4. The upper and lower center castings 12 and 13 represent gear boxes for housing the rotary mechanism that operates the rotary cutting heads mounted on the front thereof. The whole of the rotary cutting head assembly provides four additional castings or gear boxes as shown in the drawings at 14, 15, 16 and 17 which represent the upper and lower gear box castings of the left and right sides, respectively, of the machine as viewed in Figs. 3 and 4. The complementary way channels 18 and 19 in the rear face of the upper and lower castings 12 and 13 are lined for the purpose of smoothly guiding the vertical movement of these castings relative to each other.

As shown in Fig. 5, the piston and cylinder structures 20 are for the purpose of raising and lowering the castings 12 and 13 relative to one another. The cylinders 21 are for the purpose of raising and lowering the lower casting 13 relative to the body 1. As shown in Fig. 2, the cylinder 20 is supported by the lugs 22 on the back of the casting 12; whereas its piston is connected to the rearwardly extending lug 23 of the casting 13. Thus, by expanding or contracting the piston within the cylinders 20, which function as a power means the castings 12 and 13 may be moved relative to one another. As also indicated in Fig. 2, the piston and cylinder assembly 21 and its piston is pivoted to the forepart of the frame 1 by the lugs 24 adjacent the top of the machine and the lower end of the cylinder is attached to the rearwardly and upwardly extending lugs 25 on the lower casting 13. Thus the casting 13 constitutes a support on the front or forward end of the body. Thus, by manipulating the expansion and contraction of the piston and cylinder assembly 21, which function as a power means the lower casting or support 13, together with all of the parts associated therewith, may be raised or lowered relative to the body 1 of the machine or the ground upon which the machine is traversing.

As shown in Figs. 1 and 2, the diagonally opposite upper and lower corners of the gear box castings forming the rotary head assembly are provided with ways 26 and 27, 28 and 29. These ways are secured to the intermediate castings 12 and 13, respectively, and extend through the end gear box castings 14 and 16 and 15 and 17 to permit them to be moved laterally outwardly of

the intermediate gear box castings 12 and 13. As shown in Figs. 1 and 5, the upper and lower end castings 16 and 17 are provided with piston and cylinder assemblies or power means 30 and the upper and lower castings 14 and 15 are provided with the piston and cylinder assemblies or power means 31. The cylinders of these piston and cylinder assemblies are opened toward the center of the machine and the pistons extending therefrom are fastened to lugs on the intermediate castings as indicated at 32.

Thus, by expanding the cylinders 30 or 31 the end gear box castings 14, 15, 16 and 17 may be extended laterally of the intermediate gear box castings 12 and 13. It is preferable to have independent controls for the actuating of the pairs of pistons 30 and 31 to permit a selected side to be extended a selected distance rather than to require the extension of all the end castings simultaneously. However, it is preferable to have the upper and lower gear box castings on each end move laterally simultaneously.

The rotary cutting heads 33 to 40, inclusive, are each mounted on their respective shafts marked with the same reference number and indicated by the letter "a" and each of these shafts is carried by spaced bearings in the front and rear walls of their respective gear box casting members and the worm gear marked with the letter "b" is mounted on the shaft between the bearings as shown in Fig. 4. The worm gear of each shaft engages the worm marked "c" mounted on the upper and lower horizontal shafts 41 and 42. The worms 33c, 34c, 39c and 40c of the end gear box castings are each mounted in spaced bearings indicated by the letter "d" and have splined bores for receiving the splined sections on the ends of the shafts 41 and 42.

The upper horizontal shaft 41 is carried by the central bearings 43 and 44 mounted in the gear box casting 12 and the end bearings 45 and 46. The lower shaft 42 is likewise supported by bearings mounted in the intermediate casting 13, the spaced center bearings being indicated at 47 and 48 and the outer bearings indicated at 49 and 50. Thus, the upper and lower shafts 41 and 42 are supported by bearings wholly contained with the intermediate gear box castings 12 and 13 and the ends of these shafts extend laterally therebeyond and are splined so as to be slidably received in the splined bore of the corresponding worms 33c, 34c, 39c and 40c as shown in Fig. 4. Thus, upon lateral movement of the end gear box castings 14 and 15, 16 and 17 from the intermediate gear box castings 12 and 13, the upper and lower shafts remain in contact with their respective driving units which constitutes a driving means that keeps the rotary cutting members of each row operating in timed relation.

Intermediate of the central bearings of the shafts 41 and 42 a ring gear is provided, such as indicated at 51 and 52. These ring gears are likewise shown in Fig. 2 and engage the vertically disposed worms 53 and 54 carried by the vertical shaft 57. The worm 54 is supported at its ends by the bearings 56 in the gear box 13 and the worm 53 is fixed to the shaft 57 which in turn is supported by the bearings 55 in the gear box 12. The lower end of the shaft 57 is splined to operate in the splined bore in the worm 54. Thus, the vertical shaft 57 constitutes a driving means that keeps the rotary cutting members of the upper and lower rows operating in timed relation and permits the upper and lower castings to be separated from one another for raising or lowering the upper row of heads relative to the lower row of heads for the purpose of changing the height of the cut in accordance with the change in the height of the seam of coal.

The upper end of the vertical shaft 57 has secured thereto the beveled pinion 58 that engages the beveled pinion 59 on the end of the horizontal shaft of the hydraulic motor 60 secured to the rear face of the upper intermediate casting 12. In like manner, the upper end 75

of the worm 54 in the lower gear box 13 has secured thereto the beveled pinion 61 which meshes with the beveled pinion 62 on the end of the shaft of the lower hydraulic motor 63 attached to the rear face of the intermediate casting 13.

Thus, the upper and lower rows of cutting heads are driven by independent motors and are kept in timed relation by the vertical timing shaft 57 that extends between the upper and lower rows of the cutting heads. 10 Each of the hydraulic motors 60 and 63 is operated through selected controls from the hydraulic pump 9 as illustrated in Fig. 2.

Each of the cutting heads is provided with a series of bits having double cutting teeth as indicated at 64 which are mounted in radial alignment and recede rearwardly from the axially disposed pilot bits indicated at 65. The bits 64 are radially axially spaced from one another and are arranged to cut concentric kerfs or cuts within the coal. When the machine is moved 20 forward, the rotary cutting heads will advance with the teeth of the bits following their independent helices into the coal and chip or cut it free from the seam.

The upper row of cutting heads is positioned to the rear of the lower row of cutting heads to provide 25 adequate space for the coal removed by the upper cutting heads to be deposited at the front of the conveyor as indicated at 66. The cutting heads in the upper and lower rows on opposite sides of the center of the machine turn in the directions to move or convey the coal toward 30 the center of the machine from whence it is picked up by the conveyor and removed from the vicinity of the face. Thus, the shafts 33a to 36a each rotates in a counterclockwise direction as viewed in Figs. 3 and 4; whereas the shafts 37a to 40a rotate in a clockwise direction.

As indicated in Figs. 1 to 3, the lower intermediate gear box casting or support 13 has a plate 67 attached to its lower front edge and also to the depending arms 68 which are secured to the underside of the intermediate casting 13 adjacent the ends thereof as indicated in Fig. 3. The central portion of the plate 67 is cut away as indicated at 70 for the purpose of receiving the front of the conveyor 66. The lower edge of the plate 67 is provided with the horizontally disposed scraping blade 71. This scrapes, cuts and chips the cusps produced between the adjacent rotary chipping heads as indicated in Fig. 3, thereby providing a smooth mine floor over which to operate the machine. This cutting or scraping blade 71 constitutes one auxiliary cutting means supported from the body to cut an increased cross-sectional tunnel area than that defined by the combined sweep of the rotary cutting heads. This blade also cuts substantially tangentially to the outer circular cuts of the lower sweep of cutting heads. The depending arms 68 55 also carry the under transverse plate 72 which forms a pocket for supporting the front end of the conveyor 66 from the chipping head assembly.

The conveyor 66 is made up of a continuous drag chain 73 which operates on the upper and lower conveyor 60 surfaces 74 and 75 that are rigidly secured to the sides 76 and 77, as shown in Figs. 1 to 3. This conveyor trough extends rearwardly underneath the gear box casting 13 and then turns upwardly rising to the upper portion of the body of the machine as shown in Fig. 5 and extends rearwardly to a discharge end where the upper flight of the conveyor rounds a drive sprocket and continues back to the front of the machine along the lower flight. As shown in Fig. 5, the drag chain conveyor is made with three chains 73, each having spaced laterally extending drag flights as indicated at 78. The conveyor is driven at its discharge end by a hydraulic motor, not shown, which receives its power from the pump 9.

In order to remove the three intermediate cusps formed 75 between the upper row of cutting heads, the upper inter-

mediate gear box casting 12 is provided with a hinged member 80 that carries the upper scraping blade 81 which may be elevated and retracted by the cylinders 82. By manipulating the pistons in the cylinders 82 one may raise or lower the blade 81 to cut any portion of the cusps formed between the upper row of cutting heads and thereby provide a mine with a smooth ceiling as well as a smooth floor. This cutting or scraping blade 81 constitutes the other auxiliary cutting means supported from the body to cut an increased cross-sectional tunnel area than that defined by the combined sweep of the rotary cutting heads. This blade also cuts substantially tangentially to the outer circular cuts of the upper sweep of the cutting heads.

By manipulating selected controls of the hydraulic cylinders or power means, one is enabled to raise the upper row of cutting heads relative to the lower row and to space the outermost cutting heads in both the upper and lower rows from the intermediate cutting heads in order to increase the height and width of the tunnel that is being formed by the operation of these cutting heads. The bits of each rotary cutting head follow concentric paths which overlap the concentric paths of the bits on the adjacent rotary cutting heads. When the heads are expanded vertically and horizontally, they decrease their overlapped relation.

The modified cusp cutters as shown in Figs. 6 and 7 are mounted on and driven by the eccentrics 33e, 35e, 37e and 39e. Each of these eccentrics is keyed to its respective shaft by the keys 83 which are positioned to locate the greatest radius of the eccentric downwardly when the cutting heads are folded or rotated to be disposed within the dimensions of the gear box castings. The perimeter of each eccentric has an annular groove 84, one side of which is a removable ring 85 to permit the eccentric opening of the plates 86, 87, 88 and 89 to be mounted thereon. Wearing rings are employed on the eccentric parts to prevent wear of the members.

The plates 86 and 89 each have vertical sets of cusp cutting teeth 90 and 91. The single horizontal cusp cutting series 92 is carried by the plate 87 whereas the cusp cutters 93 and 94 are both carried by the plate 88. Each set of cusp cutters are in the form of teeth which are bent in the direction that they chip or cut and they are set in sockets, being held in place by the clamping plate 95. The cusp cutters 90, 91, 92 and 94 for the side and end cusps may have more teeth in their series because the heads that form these cusps may be separated vertically and horizontally. However, if the machine is designed so that the spacing between all of the rotary cutting heads is equal when they are expanded, then the cusp cutters would be the same. Thus, the length of the cusp cutter series is determined by the maximum distance between adjacent cutting head centers, either vertically or horizontally.

The end plates 86 and 89 have the parallel guide tracks 96 that fit and slide in the parallel ways 97 of the plates 87 and 88 respectively. The only time that there is relative movement between these guides and ways is when the rotary cutting heads are expanded or contracted relative to each other in changing the distances between their centers.

The eccentrics 33e and 35e rotate in the same direction and the eccentrics 37e and 39e rotate in the same direction but in the opposite direction to that of the other two eccentrics. The plates 86 and 87 thus gyrate in a counterclockwise direction while the plates 88 and 89 gyrate in a clockwise direction. In a quarter turn from that shown in Fig. 6, the plates 87 and 88 will be at the point where they are closest to each other. These plates have to cut along the lines 98 and 99 to avoid interference with each other.

Rotation of the shafts thus gyrates the plates and the teeth in the small circles as indicated in the small dotted line circles. This manner of chipping or cutting the

cusps requires materially less power than the blade 81 as shown in Figs. 1 and 2.

While, for clarity of explanation, certain preferred embodiments of this invention have been shown and described, it is to be understood that this invention is capable of many modifications, and changes in the construction and arrangement may be made therein and certain parts may be employed without conjoint use of other parts and without departing from the spirit and scope of this invention.

We claim:

1. A continuous mining machine comprising a mobile body, a plurality of gear boxes mounted forwardly of said body and connected for substantially horizontal movement relative to each other, rotary cutting heads carried by said gear boxes to be fed in unison for driving a tunnel larger than said body, interconnecting drive means between said gear boxes for revolving said cutting heads, expansion and contraction motor means for moving said gear boxes to vary the spacing between the rotary axes of said cutting heads to change the horizontal cross-sectional dimension of the tunnel while said interconnecting driving means are operative.

2. A continuous mining machine comprising a mobile body, a set of vertically disposed ways on the front of said body, upper and lower central gear boxes mounted to slide on said vertical ways, jack means for supporting and moving the lower of said gear boxes relative to said body, jack means for supporting and moving the upper gear box from and relative to the lower gear box, a set of ways projecting laterally from each side of each of said central gear boxes, an outer gear box movably mounted on each set of laterally projecting ways, a jack member for moving each of said outer gear boxes relative to the first and second central gear boxes, rotary cutting heads carried by said gear boxes, interconnected drive means carried by said gear boxes for rotating said cutting heads in timed relation to each other, and means to feed said gear boxes with their cutting members forward as a unit to cut a tunnel.

3. The structure of claim 2 characterized in that the path of rotary movement of each of said rotary cutting heads overlaps the path of rotary movement of its adjacent cutting head.

4. The structure of claim 2 characterized in that the path of each of said rotary cutting heads overlaps the path of rotary movement of its adjacent cutting heads regardless of the relative position of the gear boxes to each other.

5. A continuous coal mining machine comprising a mobile body, a plurality of gear box means mounted forwardly of said body and selectively connected for vertical and horizontal movement relative to each other, each gear box means having rotary drive means interconnected with each other to synchronize their operation, a plurality of rotary cutting heads mounted on said rotary drive means to revolve in timed relation with each other, the cutting circles of adjacent cutting heads overlapping each other to simultaneously cut a single tunnel in the coal, and motor means to separate the gear box means without interrupting the interconnected drive means to vary the overlapping relation of the cutting circles of the rotary cutting heads and thereby to change the overall dimension of the tunnel cut without disrupting the operation of the drive means.

6. The structure of claim 5 characterized in that said motor means separates the gear box means both vertically and horizontally.

7. The structure of claim 5 which also includes motor means to raise and lower said gear box means relative to said body.

8. The structure of claim 5 which also includes eccentrics on selected of said drive means, cusp cutter eccentric plate means mounted to be driven by said eccentrics to cut the cusps between adjacent cutting circles regard-

less of their overlapped relation, and slide means interconnecting the plate means on adjacent eccentrics, the axes of which move relative to each other.

9. In a mining machine, a mobile body, at least one central rotor gearbox assembly and two outboard gearbox assemblies, one on each side thereof, all mounted upon the forward end of said body, said central and outboard gearbox assemblies being positioned in slidable relationship horizontally outwardly with respect to each other, each of said gearbox assemblies being provided with at least one forwardly extending rotor shaft having cutting members thereon adapted to advance axially and mine the face in front of the machine to form a tunnel, expansible drive means for imparting rotary motion to said rotor shafts and in continuous driving relation with said shafts at all positions, and power actuated means on said machine for slidably extending and retracting said outboard gearbox assemblies horizontally to a predetermined position.

10. In a mining machine, a mobile body, at least one central rotor gearbox assembly and two outboard gearbox assemblies one on each side thereof mounted on the forward end of and in slidable relationship with respect to said body, each of said gearbox assemblies being provided with at least one forwardly extending rotor shaft having cutter members thereon adapted to advance axially and mine the face in front of the machine to form a tunnel, means for imparting rotary motion to said rotor shafts, power actuated means for extending and retracting said outboard gearbox assemblies horizontally to a predetermined position and for locking said gearbox assemblies in said position.

11. A mobile mining machine adapted to advance the whole face and remove the mined material forming a tunnel as the machine moves forward, comprising a body with a plurality of forwardly positioned and horizontally and vertically separable gearbox means, said gearbox means supporting a plurality of spaced rotary cutting members disposed on generally forwardly projecting parallel axes to mine the whole face in front of the machine when forming the tunnel through which the machine travels, characterized by drive means in each of said gearbox means for rotating the cutting members supported thereby, and power means supported from said body to vary the horizontal and vertical spacing between said gearbox means while mining and while the machine moves forward to effect a gradual change in the dimensions of the advancing face of the tunnel.

12. A mining machine adapted to cut and remove the mined material in advancing the whole face to form a tunnel as the machine moves forward comprising a powdered mobile body, a plurality of adjacent gearbox means connected for horizontal movement relative to each other and mounted on the forward end of said body, rotary shafts extending from each gearbox means, cutting members mounted on said shafts, drive means in each gearbox means for rotating said shafts in timed relation, timing means connecting the drive means of each gearbox means, motor means supported by said mobile body to actuate said drive means, and power means to change the horizontal proximity of one gearbox means relative to the other while the rotation of said cutting members subsists and the machine advances to alter the cross-sectional pattern of the combined overall cut made by said cutting members.

13. The structure of claim 12 characterized in that said gearbox means also includes a plurality of gearboxes connected for vertical movement relative to each other, timing means interposed in said drive means between the plurality of gearboxes, and power means to change the proximity of one gearbox relative to the other while the rotation of said cutting members sub-

sists to alter the cross-sectional pattern of the overall cut made by said cutting members.

14. A mining machine adapted to cut and remove the mined material in advancing the whole face to form a tunnel as the machine moves forward comprising a powered mobile body, support means on the front of said body and connected for raising and lowering movement relative to said body, power means carried by said body to raise and lower said support means, a plurality of adjacent gearbox means connected together for horizontal movement relative to each other with one gearbox means mounted on said support means, power means carried by said one gearbox means to change the proximity of other gearbox means relative thereto, rotary shafts having cutting members and extending from each gearbox means, drive means in each gearbox means for rotating said shafts in timed relation, timing means connecting the drive means of each gearbox means, and motor means supported by said mobile body to actuate said drive means.

15. A mobile mining machine having a frame on which at least a pair of gearboxes are mounted for horizontal movement relative to each other and each having cutting rotors disposed on generally forwardly projecting parallel axes and each carrying drive means for operating said cutting rotors when advancing axially into the body of the material to be mined characterized by power means interconnecting adjacent gearbox means to provide relative movement toward and away from each other to change the horizontal spacing therebetween and thus change the horizontal spacing of the cutting rotors carried by said gearbox means as the mining machine moves forward.

16. A mobile mining machine having a frame on which at least a pair of gearboxes are mounted for horizontal movement relative to each other and each having cutting rotors disposed on generally forwardly projecting parallel axes and each carrying drive means for operating said cutting rotors when advancing axially into the body of the material to be mined characterized in that the cutting rotors are laterally arranged horizontally relative to each other and power means interconnecting adjacent gearbox means to provide relative movement toward and away from each other to change the horizontal spacing therebetween and thus change the horizontal spacing of the cutting rotors carried by said gearbox means as the mining machine moves forward.

17. In a mining machine, a mobile body, at least one central gearbox assembly and at least one outboard gearbox assembly on each side thereof mounted forwardly of and supported from said body for movement relative thereto, said outboard gearbox assemblies being positioned in slidable relationship horizontally with respect to said central gearbox assembly, each of said gearbox assemblies being provided with at least one forwardly extending rotor shaft having a cutting member thereon, drive means carried by said gearbox assemblies for imparting rotary motion to said rotor shafts, power actuated means interconnecting said gearbox assemblies for slidably extending and retracting the said outboard assemblies horizontally, and power means to raise and lower said gearbox assemblies relative to said body.
